TRAIN-CONTROL SYSTEM.

Application filed December 19, 1923. Serial No. 681,569.

This invention relates to a train control system, and more particularly to a system for controlling the movement of trains automatically by roadside mechanism and manually by the engineman on the train; and has special reference to the provision of a system in which automatic control is so combined with manual control as to assure absolute safety in the running of trains while necessitating alertness on the part of the engineman for producing efficient and expeditious train movement.

One of the principal objects of our present invention comprehends the provision of a train control system in which train carried mechanism for governing the operation of the train is automatically controlled by roadside mechanism operable in accordance with roadside conditions in such a manner that the running operation of the train under unsafe traffic conditions is made dependent only upon such traffic conditions, and in which the cooperative control by the engineman is made necessary so as to supplement the automatic control for producing the proper dispatch in the movement of trains.

A further and more specific object of our invention includes the provision of a train control system in which the train carried and roadside mechanism cooperate to produce train indications in response to "clear", "caution" and "danger" conditions, and in which the movement of the train is controlled each time that the train carried mechanism passes a roadside control station imposing a restrictive running condition, the train being so controlled as to bring the same to a halt when the restrictive condition is either a "caution" or "danger" condition, the restrictive imposed condition being, however, modifiable by the intervention of the engineman to permit continued movement of the train under a restrictive speed.

A still further and ancillary object of the invention comprehends the provision of a system of the nature referred to in which a manual operation on the part of the engineman is necessitated when the train carried mechanism is changed in response to the indications of the roadside mechanism and in which such manual intervention becomes ef-

fective only after the vehicle carried mechanism has been changed and after the movement of the vehicle has been reduced to a permissive speed.

55

To the accomplishment of the foregoing and such other objects as may hereinafter appear, our invention consists in the elements and their relation one to the other, as hereinafter particularly described and sought to be defined in the claims, reference being had to the accompanying drawing showing the preferred embodiment of our invention, and in which:

60

Fig. 1 is a diagrammatic view showing the vehicle carried apparatus and circuits and part of the roadside apparatus cooperating therewith, and

65

Fig. 2 is a diagrammatic view of a modification thereof.

70

In the train control system of our present invention, for directly controlling the movement of the train there is provided an electrically operated device for controlling the operation of the air brake system, the said device being under the control of cooperating train and roadside mechanism and being operated thereby in accordance with roadside conditions. The electrically operated device comprises in the preferred construction an electromagnet 10 which controls the operation of a combined reservoir and brake valve of the type disclosed in the patent to A. G. Shaver, No. 1,411,526 of April 4, 1922, and in the copending application of Allen B. Kendall, Ser. No. 443,046 of Feb. 7, 1921, the said reservoir and brake valve functioning upon the deenergization of the electromagnet 10 for cutting off the supply of air from the main reservoir of the air brake system to the engineman's brake valve and for opening the train pipe to exhaust, the electromagnet 10 being normally energized to hold open the communication between the main reservoir and the engineman's brake valve and to close the train pipe to exhaust.

80

For normally controlling the operation of the electromagnet 10 there is provided a train carried circuit which is normally energized as under "clear" roadside conditions by a train carried source of energy such as the battery 11, the said circuit in-

85

90

95

100

cluding the resistance r , conductors 12 and 13, a movable make and break indicating means 14 which is operable in response to roadside conditions as will be detailed hereinafter to assume any one of the three positions a , b and c , the full line inclined position a corresponding to the "normal" or "clear" position, the inclined dotted position b corresponding to one of the "non-clear" 10 positions such as the "caution" position, and the vertical dotted line position c corresponding to another "non-clear" such as the "danger" position, the said circuit further including the conductors 15, 16 and 17, electromagnet 10, and conductors 18, 19 and 20. Under "normal" or "clear" conditions with the indicating means 14 in the position a , the brake controlling magnet is energized to permit the vehicle to proceed.

20 To operate the brake controlling magnet 10 in response to and in accordance with roadside or traffic conditions, there are provided cooperating train and roadside mechanisms which function to cause the make and break indicating means 14 and also a make and break indicating means 14' shown in Fig. 1 to be operated selectively to the positions a , a' ; b , b' ; and c , c' ; the position a' of the make and break means 14' being that assumed under "clear" conditions corresponding to the position a of the make and break means 14, the position b' being that assumed under "caution" conditions, and the position c' being that assumed under "danger" conditions.

The train and roadside mechanisms for controlling the action of the indicating make and break means include the provision of a roadside energy transmitting means which 40 in the present form of our invention comprises a plurality of ramp rails spaced along the roadside, a rail such as indicated at 21 being provided for each section or block of the track; the said ramp rail comprising means for transmitting energy to a train carried shoe mechanism 22 under "safe" 45 roadside conditions, such energy being transmitted in turn to a translating device such as the indication selector I, the action of which directly controls the operation of the make and break means 14, 14'.

The indication selector I preferably comprises a unit such as is disclosed in the pending application of Theodore Bodde, Ser. No. 634,059, of April 23, 1923, the indication selector comprising a stator 23 and a rotor 24 movable into any one of three positions for operating the make and break means 14, 14', said positions including the 55 normal position a^2 , the "caution" position b^2 and the "danger" position c^2 , corresponding to the positions a , b and c simultaneously assumed by the make and break means 14, the position a^2 being produced by energizing the 60 stator magnet 23 with a current of a given

polarity, the position b^2 being assumed by energizing the stator magnet with a current of a reverse polarity, and the position c^2 being assumed when the magnet is unenergized. The indication selector further includes a locking device 25 controlled by an electromagnet 26 and operative for engaging a notch 27 in the rotor 24 to lock the same in the "neutral" or "danger" position.

The electromagnets 23 and 26 are arranged in series and connected in a partial circuit to the shoe 22 and to the frame of the vehicle represented by the ground connection 28 by means of the conductors 29 and 30 respectively, the construction being such that when the shoe 22 rides the ramp 21 the said partial circuit will cooperate with a roadside partial circuit (not shown) connected to the ramp 21 and to the rails, as is disclosed for example in the application of 75 A. G. Shaver Ser. No. 292,548, filed May 25, 1919, the cooperation being such that under "normal" or "clear" roadside conditions the ramp 21 will be energized by current of a given polarity to correspondingly energize 80 the stator magnet 23, and under an "unclear" such as a "caution" condition the ramp 21 will be energized by current of an opposite polarity to correspondingly energize the magnet 23, and under a "danger" roadside 85 condition the ramp 21 will be deenergized so that the magnet 23 is unenergized when the shoe rides the ramp.

For holding or maintaining the rotor 24 of the indication selector and the make and break means 14 and 14' in the positions to which these parts are actuated when the shoe moves over the ramp, the indication selector includes a holding circuit which is broken when the shoe moves over the ramp to permit freedom of action of the moving parts in response to energization of the stator magnet 23, and which is closed when the shoe disengages the ramp, the said holding circuit comprising an electromagnet 31 having the pole pieces 32 and 33 selectively operable for cooperating with the armature 34 of the rotor 24 to hold the same in either the positions a^2 or b^2 , the holding circuit further including the conductor 35, the relatively stationary contacts 36 and 37 normally bridged by the conducting piece 38 fixed to and movable with the shoe 22, conductors 39, 40 and 20, battery 11, resistance r , conductor 12, conductors 41 and 42, relatively stationary contacts 43 and 44 normally bridged by the conducting piece 45 which is also fixed to and movable with the shoe 22, and conductor 45' connected to the holding magnet 31. This circuit is normally closed 110 as traced, and when the shoe engages the ramp the circuit is broken at the contacts 36 and 44 to effect the deenergization of the holding magnet 31 and permit the freedom of motion and operation of the rotor by the 115

action of the magnet 23. When the shoe leaves the ramp this circuit is again closed at the contacts 36 and 44 for reenergizing the holding magnet 31 to hold the armature 34 in either the position a^2 or b^2 to which it has been operated by the energization of the magnet 23.

As heretofore mentioned, in accordance with our present invention it is desired to operate trains by a combined automatic and manual control, the train being automatically controlled by roadside mechanism in accordance with roadside or traffic conditions, the automatic control being supplemented by a manual control to prevent or modify the automatic operation if the engineman is alert and is acting in obedience to the indications of a roadside signalling system. To compel alertness, it is contemplated by the present invention to produce an automatic operation to bring the vehicle to a low restrictive speed condition such as a halt or stop whenever an "unsafe" such as a "caution" or "danger" indication is received by the vehicle mechanism, this automatic stop being produced irrespective of the speed of the vehicle when passing such an indication ramp, the "stop" for this condition, however, being preventable or modifiable by the engineman to permit the train to proceed under a restrictive speed. In the system of our present invention, it is furthermore desired to permit modification of the condition imposed by the roadside mechanism when and only when a change of indication has been received by the vehicle carried mechanism combined with a reduction of the speed of the vehicle to or below a permissive speed corresponding to the indication.

For producing this operation when a "caution" block is being approached or has been entered, and more specifically when the indicating means 14, 14' is moved from the "clear" position a to the "caution" position b , we provide a medium permissive speed control circuit for controlling the operation of the brake controlling magnet 10, this circuit being under the control of a speed controller 46 operable in accordance with the speed of the vehicle, the circuit being further under the control of the make and break indicating means 14 and of a contact mechanism 47, the circuit comprising battery 11, the resistance r , conductors 12 and 13, indicating means 14 in the position b , conductor 48, medium speed contact 49 closed by the controller 46 when the speed of the vehicle reaches a medium permissive speed, common contact 50, conductor 51, conductor 52, a switch mechanism 53 provided for a purpose which will appear more in detail hereinafter, conductor 54, conductors 55 and 56, contact mechanism 47 normally open, front contact 57, conductor 58, a relay

59, conductor 60, and conductors 19 and 20. This circuit under "clear" running conditions is open at the indicating means 14 and at the contact mechanism 47, and when the train is running above the medium permissive speed permitted under "clear" running conditions is also open at the contact 49. It will be apparent with this circuit arrangement that when the indicating means 14 is moved to the "caution" position b , and when the speed of the train has been reduced to the medium permissive speed, the circuit will be in a condition to be closed upon the closing of the contact mechanism 47, 57, and that the circuit will be maintained closed by the continued energization of the relay 59, the said relay in association with the contact mechanism comprising a stick relay.

This medium speed control circuit controls the electromagnet 10 so that if the circuit is closed and maintained closed, the electromagnet 10 will be energized to permit the train to proceed, this being accomplished by placing the electromagnet 10 in parallel with the relay 59 and contact mechanism 47, 57 by means of the conductor 18, conductor 17, conductor 61, a contact mechanism 62 connected mechanically to the contact mechanism 47 by a stem 63, a front contact 64, and conductor 65. Thus upon the closing of the contact mechanism 47, 57, the contact mechanism 62, 64 will also be closed and the brake controlling magnet 10 energized.

With the provision of this medium speed control means for the electromagnet 10, it will be manifest that when the vehicle carried shoe rides a "caution" ramp, the normal control circuit for the electromagnet 10 will be broken by the change of indication of the make and break means 14 from position a to b and that upon such change of indication the electromagnet 10 will be automatically operated and deenergized to bring the vehicle to a halt. This automatic operation, however, may be forestalled or modified by the engineman if he is alert, and provided he is acting in conformity with roadside requirements by reducing the speed of the train to or below the medium speed limit, the reduction of the speed of the train closing the medium speed control circuit at the contact 49 and the alertness of the engineman consisting in his intervention by the manual operation of the contact mechanisms 47 and 62 to circuit closing position. It will be evident, however, that the medium speed control circuit cannot be closed unless the reduction of the speed of the train and the manual intervention are combined with the change of indication of the indication selector so that forestalling or modifying the operation of the brake controlling magnet is possible only during the time when or after the shoe rides the ramp

and after the speed of the train has been reduced to a "safe" or permissive speed. It will also be apparent that if this speed is exceeded the contact 49 will be opened, opening and maintaining open the medium speed circuit at the stick relay mechanism, necessitating the further manual intervention of the engineman after the speed has again been reduced.

10 For producing the desired automatic-manual operation when a vehicle running "clear" is approaching or enters a "danger" block and more specifically when the indicating means 14, 14' is moved from "clear" to the 15 "danger" position, we provide a low permissive speed circuit for controlling the operation of the electro-magnet 10, this circuit comprising the battery 11, resistance r , conductors 12 and 41, contact 66, the indicating 20 means 14' which is open in positions a' or b' and which is closed only in the position c' when a "danger" indication has been received, contact 67, conductor 68, low speed control contact 69, speed controller 46, common contact 50, conductors 51 and 52, switch means 53, conductors 54, 55 and 56, contact mechanism 47, 57 normally open, conductors 58, relay 59, and conductors 60, 19 and 20. This circuit, it will be noted, is similar to 25 the medium speed control circuit so that when a "danger" indication is received the electromagnet 10 will be deenergized by the opening of the indicating means 14 to bring the vehicle to a halt in the absence of any 30 intervention on the part of the engineman, and that such intervention will forestall or modify the automatic control and permit the vehicle to proceed under a restrictive speed provided that the indicating means 14' has 35 been moved to the "danger" position c' , and provided further that the speed of the train has been reduced to the low permissive speed for closing the speed controller contact 69. It will be further evident that by the 40 manual intervention of the engineman and the operation of the contact mechanism 47 and 62, the train is placed under the control of the low permissive speed so that the train is permitted to proceed only when running at 45 or below the low permissive speed, and that if this speed is exceeded, the contact 69 will be opened, opening and maintaining open the low speed circuit at the stick relay mechanism, necessitating the further manual intervention of the engineman after the speed 50 has again been reduced.

The automatic-manual control above described is also produced when the change of indication is from "caution" to "danger." 60 When this change of indication is effected, the indicating means 14 moves from the position b to c , opening the medium speed control circuit and effecting the deenergization of the stick relay 59, and thus without a 65 further intervention on the part of the en-

gineman, all the circuits controlling the electromagnet 10 will be open to bring the vehicle to a halt. However, with the assumption of the position c' by the indicating means 14', the low speed control circuit is 70 now in a condition to be closed by the manual operation of the contact mechanism 47 provided the speed of the train has been reduced to or below the low speed limit, forestalling or modifying the automatic operation 75 being therefore possible only after the change of indication has been received and after the restrictive speed has been assumed.

For manually operating the contact mechanism 47, 62 we preferably provide a controlling means of the type disclosed in the application of A. G. Shaver, Serial No. 634,053 of April 23, 1923, the said circuit controlling means generally comprising the stem part 63 heretofore referred to and a 80 push button part 69 so inter-related with the stem part that an actuation of the push button will produce a single mechanical impulse operation of the stem 63 so that if the stick relay 59 is not energized by closing of the contact mechanism 47, the stem and the connected contact parts will move to open position independently of the return of the push button device to normal position. With this construction, it will be noted 85 that the push button cannot be held by the engineman in its ascended position so as to thwart or negative the operation of the automatic control mechanism, the integrity of the control of the stick relay by means 90 of the indication selector and the speed controller being thereby maintained.

For the purpose of informing the engineman when the operation of the push button will be fruitful in forestalling or modifying an automatic operation of the electromagnet 10, and more specifically when the train has been brought to or below the pre-determined speed, we provide a signalling means 70 which may comprise a lamp connected to the conductor 40 by means of a conductor 71 and to a back contact 72 by means of a conductor 73. With this circuit arrangement, it will be manifest that:

a. Under "clear" running conditions irrespective of the speed of the vehicle the signalling means 70 will be unenergized, since the medium speed and low speed circuits are open at the indicating means 14, 14'.

b. When, however, the indicating means 120 14 assumes the position b under a "caution" indication, the signalling means will be unenergized if the vehicle is above the medium restrictive speed, and will become energized only when the medium speed limit is 125 reached, thus informing the engineman that the manual operation of his push key will make effective the medium speed control circuit, and

c. When the indicating means 14' assumes 130

the position *c'* under a "danger" indication, the signalling means 70 will become energized only when the speed of the train has been reduced to the low permissive speed, 5 thus informing the engineman that under this condition his manual intervention will be effective for making operative the low speed control circuit.

It may at times be desirable to enforce 10 an acknowledgment on the part of the engineman when the train running under a restriction passes a control station imposing the same restriction, as for example when a train running under "caution" conditions 15 moves over a second "caution" ramp or when a train moving under "danger" conditions passes a second "danger" ramp. To enforce such an acknowledgment, the switch means 53, heretofore mentioned is provided, this 20 switch means being normally closed and being opened by a finger 74 attached to and movable with the shoe 22, with the construction such that during the elevation of the shoe, the switch 53 is opened, and when the 25 shoe is in the elevated position, as well as when the shoe is moved to the descended position, the switch means 53 is closed. Since the switch 53 is placed in a part common 30 to both the medium and low speed control circuits, it will be seen that if either of these circuits is operative (during "caution" or "danger" running), the opening of the switch means will open either of these circuits, necessitating the manual control of 35 the stick relay mechanism. It will be understood, however, that this control may be eliminated if desired by the elimination of the conductors 52 and 54 and switch means 53, and by the direct connection of 40 the conductors 51 and 55.

Referring now to Fig. 2 of the drawings, we show a modification of our system in which with certain changes of indication, such as from "clear" to "danger," the fore- 45 stalling or the prevention of the automatic operation may be made effective prior as well as subsequent to the change of indication; and under other conditions, as when the indication changes from "caution" to 50 "danger," no acknowledgement on the part of the engineman is necessary provided the train has been reduced to the permissive speed under a "danger" indication.

Referring more in detail to Fig. 2, the 55 shoe mechanism, the ramp, the indication selector, the speed controller, and the brake controlling magnet are substantially of the same construction as that heretofore described in connection with Fig. 1, and are 60 indicated by similar reference characters. The stick relay 59', however, is of the slow releasing type.

Under "normal" running conditions the 65 electromagnet 10 is energized by the circuit comprising the battery 11, resistance *r*, con-

ductor 13, make and break means 14 in position *a*, conductor 15, back contact 75, contact mechanism 62, and conductors 61, 17, 18 and 20.

Upon a change of indication from "clear" 70 to "caution" the indicating means 14 is moved from the position *a* to position *b*, breaking the normal circuit for the electromagnet 10, the medium speed control circuit being in a position to be closed by intervention of the engineman provided the speed 75 has been reduced to the medium limit, the said circuit comprising the battery 11, resistance *r*, conductor 13, indicating means 14 in position *b*, conductor 48, contact 49, speed controller 46, common contact 50, conductor 51, contact mechanism 47, front contact 57, conductor 58, slow release relay 59', conductors 60 and 20. When this circuit is closed the electromagnet 10 is energized, this 80 electromagnet being connected in parallel with the stick relay 59' and its contact mechanism 47, 57 by means of the conductors 18, 17, 61, contact mechanism 62, front contact 64, and conductor 65'. Thus with a change 85 from "clear" to "caution", the operation is 90 similar to that heretofore described for Fig. 1.

In the system in Fig. 2, however, the low 95 speed control circuit is not under the control of the indication selector and is independent thereof, so that the low speed control circuit may be made effective before, during or after a change of indication has been produced provided the speed of the train is at or be- 100 low the low permissive speed. This low speed control circuit comprises the battery 11, resistance *r*, conductor 76, contact 77, speed controller 46, contact 50, conductor 51, contact mechanism 47, 57, conductor 58, re- 105 lay 59', and conductors 60 and 20. Thus with a change of indication from "clear" to "danger" an acknowledgement on the part of the engineman is made necessary by the 110 operation of the push key 69', which acknowledgement may be made, however, prior to the shoe 22 passing the ramp 21, the low speed control circuit becoming effective if the speed is below the low permissive limit.

With this described arrangement, it will 115 be also understood that when the indication selector is operated to produce a change from "clear" to "caution", while the placing of the train under the medium restrictive speed is made possible only after a change of indication is produced, as heretofore recited, the placing of the train under the control of the low permissive speed is possible either before or after the change of indication is produced provided the speed of the train 120 is at or below the low limit.

Upon a change of indication from "caution" to "danger", with the system shown in Fig. 2, since the medium speed control circuit is closed at the contact mechanism 47, 130

57, no further acknowledgement on the part of the engineman is necessitated upon or after passing the "danger" ramp if the train has been reduced to the low permissive speed 5 in accordance with the "danger" condition.

The operation of our train control system will in the main be fully apparent from the above detailed description thereof. It will be further apparent that with the provision 10 of our system, the proper manual control and operation of the train is enforced by the imposition of a train control effect which is more stringent or restrictive than that necessitated by the roadside condition, placing the full burden of efficient dispatch of the train upon the engineman, and the train is automatically controlled to prevent any misuse or mis-operation of the train in disregard of roadside requirements. It will be 20 further noted that a plurality of indications and a plurality of speed restrictions may be imposed or produced by means of simple co-ordinated mechanism, each instrumentality being controllable either automatically 25 or manually for producing the different running conditions.

While we have shown our invention in the preferred forms, it will be apparent that numerous changes and modifications may 30 be made in the structure disclosed without departing from the spirit of the invention, defined in the following claims.

We claim:

1. In a manual-automatic speed control 35 system for vehicles, a vehicle carried mechanism comprising a device for controlling the movement of the vehicle, an indicating means operable in response to roadside conditions for producing a "clear" or "non-clear" indication, means under the control of said indicating means in "clear" indicating position for producing a normal operation of the said device, additional means under the control of the speed of the train and 40 of said indicating means in "non-clear" indicating position for controlling the operation of the said device so that when and only when the indicating means is changed from its "clear" to its "non-clear" position and the speed of the vehicle is at or below a permissive speed, the said device may be 45 operated by intervention of the engineman to maintain its normal operation but without such intervention and with the change 50 of the indicating means to the "non-clear" position the device will be automatically operated to reduce the speed of the vehicle, such automatic operation persisting regardless of the subsequent decrease of speed of 55 the vehicle below the permissive speed, and manual means under the control of the engineman for operating the said additional means to restore the normal operation of the device when the speed of the vehicle has 60 been reduced to or below the said permissive 65

speed so as to permit vehicle movement at or below such speed.

2. In a manual-automatic speed control system for vehicles, vehicle carried mechanism comprising an electrically operated device, a make and break indicating means operable into a "clear" or "non-clear" position, a speed controlled contact mechanism, a normally operative circuit for the device controlled by the indicating means in "clear" 70 position, a second and normally inoperative circuit for the device controlled by the contact mechanism and the make and break indicating means in the "non-clear" position, the said second circuit being operable so that when and only when the indicating means is operated from its "clear" to its "non-clear" position and the speed of the vehicle is reduced from a speed above to a speed at or below a permissive speed, the circuit is in a condition to be operated by intervention of the engineman to maintain the normal operation of said device but without such intervention will remain inoperative so that the change of the indicating means to the "non-clear" position will automatically operate the device to reduce the speed of the vehicle, such operation persisting regardless of the subsequent decrease of speed of the vehicle below the said permissive speed and manual means for operating the said second circuit when the speed of the vehicle has been reduced to or below the said permissive speed so as to permit vehicle 90 movement at or below such speed. 100

3. In a manual-automatic speed control system for vehicles, vehicle carried mechanism comprising an electrically operated device, a make and break indicating means operable into a "clear" or "non-clear" position, a speed controlled contact mechanism, a normally closed circuit for energizing the device controlled by the indicating means in "clear" position, a second and normally open circuit for the device controlled by the 105 contact mechanism and the make and break indicating means in the "non-clear" position, the said second circuit being operable so that when and only when the indicating means is operated from its "clear" to its "non-clear" position and the speed of the vehicle is reduced from a speed above to a speed at or below a permissive speed, the circuit is in a condition to be closed by intervention of the engineman to maintain the 110 normal energization of said device but without such intervention will remain open so that the change of the indicating means to the "non-clear" position will automatically deenergize the device, such deenergization 115 persisting regardless of the subsequent decrease of speed of the vehicle below the said permissive speed and manual means for closing the said second circuit effective when the speed of the vehicle has been reduced 120 125 130

to or below the said permissive speed so as to again energize the device to permit vehicle movement at or below such speed.

4. A manual-automatic speed control system for vehicles, comprising vehicle carried mechanism including an electrically operated device, a make and break indicating means operable into a "clear" or "non-clear" position, a speed controlled contact mechanism, a normally operative circuit for the device controlled by the indicating means in "clear" position, a second and normally inoperative circuit for the device controlled by the contact mechanism and the make and break indicating means in the "non-clear" position, the said second circuit being operative so that when and only when the indicating means is operated from its "clear" to its "non-clear" position and the speed of the vehicle is reduced from a speed above to a speed at or below a permissive speed, the circuit is in a condition to be operated by intervention of the engineman to maintain the normal operation of said device but without such intervention will remain inoperative so that the change of the indicating means to the "non-clear" position will automatically operate the device to reduce the speed of the vehicle, such operation persisting regardless of the subsequent decrease of speed of the vehicle below the said permissive speed, manual means for operating the said second circuit when the speed of the vehicle has been reduced to or below the said permissive speed so as to permit vehicle movement at or below such speed, and intermittently effective roadside mechanism for operating the indicating means to its "clear" or "non-clear" positions.
5. In a manual-automatic speed control system for vehicles, vehicle carried mechanism comprising an electrically operated device, a make and break indicating means operable into a "clear" or "non-clear" position, a contact mechanism, a speed controlled contact mechanism, a normally operative circuit connecting the device and the make and break indicating means in "clear" position, a second and normally inoperative circuit for controlling the device and connecting the contact mechanism, the speed controlled contact mechanism and the make and break indicating means operable so that when and only when the indicating means is operated to its non-clear position and the speed of the vehicle is reduced from a speed above to a speed at or below a permissive speed the said device may be operated by intervention of the engineman to maintain its normal operation but without such intervention and with a change of the indicating means to the non-clear position, the device will be automatically operated to an abnormal condition and such automatic operation will persist regardless of the subsequent decrease of the speed of the vehicle below

the permissive speed, and manual means under the control of the engineman for operating the said contact mechanism when the speed of the vehicle has been reduced to or below the permissive speed to render the said second circuit operative for restoring the normal operation of the device.

6. In a manual-automatic speed control system for vehicles, vehicle carried mechanism comprising a device for controlling the movement of the vehicle, an indicating means operable in response to roadside conditions for producing a "clear" or "non-clear" indication, means under the control of said indicating means in "clear" position for producing a normal operation of the said device, means under the control of the speed of the train and of said indicating means in "non-clear" position for controlling the operation of the said device so that when and only when the indicating means is operated from its "clear" to its "non-clear" position and the speed of the vehicle is at or below a permissive speed, the said device may be operated by intervention of the engineman to maintain its normal operation upon a change of the indicating means to the "non-clear" position but without such intervention and with a change of the indicating means to the "non-clear" position, will be automatically operated to reduce the speed of the vehicle.

7. In a manual-automatic speed control system for vehicles, vehicle carried mechanism comprising an electrically operated device, a make and break indicating means operable into a "clear" or "non-clear" position, a stick relay contact mechanism, a speed controlled contact mechanism, a circuit for controlling the device and connecting the stick relay contact mechanism, the speed controlled contact mechanism and the make and break indicating means in "non-clear" position, the circuit being normally open at the stick contact mechanism and at the make and break mechanism in "non-clear" position, and being operable so that when and only when the indicating means is operated to its "non-clear" position and when the speed of the vehicle is moving at or below a permissive speed the said stick contact mechanism may be operated by intervention of the engineman to close the circuit and maintain the same closed for maintaining a normal operation of said device but without such intervention and with the change of the indicating means to the "non-clear" position, the circuit will remain open to produce an abnormal operation of the device.

8. In a manual-automatic speed control system for vehicles, vehicle carried mechanism comprising a device for controlling the movement of the vehicle, an indicating means operable in accordance with roadside conditions for indicating "clear", "cau-

tion" and "danger" conditions, means for operating the device to permit movement of the vehicle above a medium permissive speed when the indicating means indicates 5 "clear" and for automatically operating said device to bring the vehicle to a halt when the indicating means changes from "clear" to "caution" or from "clear" to "danger", and means operable by the engineman effective only when such a change of indication is produced for preventing or modifying the automatic operation of said device provided that the speed of the vehicle is at or below the medium permissive speed if the indicating means is changed from "clear" to "caution" and is at or below a low permissive speed if the indicating means changes from "clear" to "danger".

9. In a manual-automatic speed control system for vehicles, vehicle carried mechanism comprising a device for controlling the movement of the vehicle, an indicating means operable in accordance with roadside conditions for indicating "clear", "caution" and "danger" conditions, means for operating the device to permit movement of the vehicle above a medium permissive speed when the indicating means indicates "clear" and for automatically operating said device 20 to bring the vehicle to a halt when the indicating means changes from "clear" to "caution" or from "clear" to "danger", and means operable by the engineman effective only when such a change of indication is produced for preventing or modifying the automatic operation of said device and for placing the said device under the control of the speed of the vehicle provided that the speed of the vehicle is at or below the medium permissive speed if the indicating means is changed from "clear" to "caution" and is at or below a low permissive speed if the indicating means changes from "clear" to "danger".

45 10. In a manual-automatic speed control system for vehicles, vehicle carried mechanism comprising a device for controlling the movement of a vehicle, an indicating means operable in accordance with roadside conditions for indicating "clear", "caution" and "danger" conditions, means for operating the device to permit movement of the vehicle above a medium permissive speed when the indicating means indicates "clear" and for automatically operating said device to bring the vehicle to a halt when the indicating means changes from "clear" to "caution" or from "clear" to "danger", and means operable by the engineman and effective only when the change of indication of the indicating means from "clear" to "caution" is produced for preventing or modifying the automatic operation of said device and for placing the vehicle under the control of the medium permissive speed provided that the speed of

the vehicle is at or below said permissive speed, and means operable by the engineman and effective only when the change of indication from "clear" to "danger" is produced for preventing or modifying the automatic operation of the device and for placing the same under the control of the low permissive speed provided that the vehicle speed is at or below the low permissive speed.

11. In a manual-automatic speed control system for vehicles, vehicle carried mechanism comprising a device for controlling the movement of the vehicle, an indicating means operable in accordance with roadside conditions for indicating "clear", "caution" and "danger" conditions, means for operating the device to permit movement of the vehicle above a medium permissive speed when the indicating means indicates "clear" and for automatically operating said device to bring the vehicle to a halt when the indicating means changes from "clear" to "caution" or from "clear" to "danger", and means operable by the engineman effective only when such a change of indication is produced for preventing or modifying the automatic operation of said device provided that the speed of the vehicle is at or below the medium permissive speed if the indicating means is changed from "clear" to "caution" and is at or below a low permissive speed if the indicating means changes from "clear" to "danger", and signalling means for indicating to the engineman when with a change of indication from "clear" to "caution" the speed of the vehicle reaches the medium permissive speed and when with a change of indication from "clear" to "danger" the speed of the vehicle reaches the medium permissive speed.

12. In combination with the manual-automatic speed control system of claim 1, signalling means for indicating to the engineman when with the change of indication of the indicating means from "clear" to "non-clear" the speed of the vehicle reaches the medium permissive speed.

13. In a manual-automatic speed control system for vehicles, vehicle carried mechanism comprising a device for controlling the movement of the vehicle, an indicating means operable in accordance with roadside conditions for indicating "caution" and "danger" conditions, means for operating the device to permit movement of the vehicle below a medium permissive speed when the indicating means indicates "caution" and for automatically operating said device to bring the vehicle to a halt when the indicating means changes from "caution" to "danger", and means operable by the engineman both when or after the indicating means changes from "caution" to "danger" for preventing or modifying the automatic operation of said device provided that the speed

of the vehicle is at or below a low permissive speed.

14. In a manual-automatic speed control system for vehicles, vehicle carried mechanism comprising a device for controlling the movement of the vehicle, an indicating means operable in accordance with roadside conditions for indicating "caution" and "danger" conditions, means for operating the device to permit movement of the vehicle below a medium permissive speed when the indicating means indicates "caution" and for automatically operating said device to bring the vehicle to a halt when the indicating means changes from "caution" to "danger", and means operable by the engineman both when or after the indicating means changes from "caution" to "danger" and effective only when the change of indication is produced for preventing or modifying the automatic operation of said device provided that the speed of the vehicle is at or below a low permissive speed.

15. In a manual-automatic speed control system for vehicles, vehicle carried mechanism comprising a device for controlling the movement of the vehicle, an indicating means operable in accordance with roadside conditions for indicating "clear," "caution" and "danger" conditions, means for operating the device to permit movement of the vehicle above a medium permissive speed when the indicating means indicates "clear", to permit movement below a medium permissive speed when the indicating means indicates "caution", to also permit movement below a low permissive speed when the indicating means indicates "danger", and for automatically operating said device to bring the vehicle to a halt when the indicating means changes from "clear" to "caution" or from "clear" to "danger" or from "caution" to "danger", and means operable by the engineman for preventing or modifying the automatic operation of said device to permit the train to move at the permissive speeds provided that the speed of the vehicle is at or below the medium permissive speed if the change of indication is from "clear" to "caution", and at or below the low permissive speed if the change of indication is either from "clear" to "danger" or from "caution" to "danger".

16. In a manual-automatic speed control system for vehicles, vehicle carried mechanism comprising a device for controlling the movement of the vehicle, an indicating means operable in accordance with roadside conditions for indicating "clear", "caution" and "danger" conditions, means for operating the device to permit movement of the vehicle above a medium permissive speed when the indicating means indicates "clear", to permit movement below a medium permissive speed when the indicating means in-

dicates "caution", to also permit movement below a low permissive speed when the indicating means indicates "danger" and for automatically operating said device to bring the vehicle to a halt when the indicating means changes from "clear" to "caution" or from "clear" to "danger" or from "caution" to "danger", and means operable by the engineman effective only when a change of indication is produced for preventing or modifying the automatic operation of said device to permit the train to move at the permissive speeds provided that the speed of the vehicle is at or below the medium permissive speed if the change of indication is from "clear" to "caution", and at or below the low permissive speed if the change of indication is either from "clear" to "danger" or from "caution" to "danger".

17. In a manual-automatic speed control system for vehicles, a vehicle carried electrically operated device, a vehicle carried make and break indicating means, a speed controlled contact mechanism, a normally inoperative circuit for the device controlled by the contact mechanism and the make and break indicating means, the said circuit being operable so that when the indicating means is operated to close the make and break means and the speed of the vehicle is reduced to or below a permissive speed, the circuit is in a condition to be operated by intervention of the engineman to maintain a normal operation of said device but without said intervention will remain inoperative, manual means operable by the engineman for rendering the said circuit operative when the make and break means is closed and the speed is at or below the permissive speed, and cooperative roadside and vehicle carried means for intermittently affecting the said circuit in the movement of the vehicle to render the same inoperative regardless of the position of the make and break means whereby intermittent manual intervention is necessitated.

18. In a manual-automatic speed control system for vehicles, a vehicle carried electrically operated device, a make and break indicating means, a speed controlled contact mechanism, a stick relay contact mechanism, a normally inoperative circuit for the device controlled combinedly by said contact mechanisms and the make and break indicating means, the said circuit being operable so that when the make and break means is closed and the speed of the vehicle is reduced to or below a permissive speed to close the speed controlled contact mechanism, the circuit is in a condition to be operated by the manual closing of the stick relay contact mechanism, means operable by the engineman for closing said stick relay contact mechanism, and cooperative vehicle and roadside means for intermittently affecting

the said circuit in the movement of the vehicle to render the same inoperative regardless of the condition of the make and break means whereby the said circuit if operative will be rendered inoperative at the stick relay contact mechanism so that intermittent manual intervention on the part of the engineman is necessitated.
